UNITED STATES PATENT OFFICE.

RICHARD A. GRIEFEN, OF CHICAGO, ILLINOIS.

STORM-SHIELD.

1,126,754.

Specification of Letters Patent.

Patented Feb. 2, 1915.

Application filed February 12, 1912. Serial No. 748,062.

To all whom it may concern:

Be it known that I, RICHARD A. GRIEFEN, a citizen of the United States, residing at Chicago, in the county of Cook and State of Illinois, have invented certain new and useful Improvements in Storm-Shields, of which the following is a specification.

This invention relates in general to storm shields and has more particular reference to shields adapted for use in connection with limousine automobiles, and the like, to prevent sleet, rain, snow, etc., from lodging against the front glass so as to obscure the driver's vision.

One of the primary objects of the invention is to provide a disappearing shield which can be housed within the top of the vehicle when not in use and which can be readily and quickly arranged in operative position over the front glass when required.

Other objects and advantages of the invention will be readily apparent to those skilled in the art as the same is better understood by reference to the following description when considered in connection with the accompanying drawings.

Referring to the drawings—Figure 1 is a fragmentary front elevation of a limousine equipped with my invention; and Fig. 2 is a fragmentary longitudinal sectional view taken on the line 2—2 of Fig. 1.

On the drawings reference character 5 designates the sides, 6 the top and 7 the front of a vehicle body of usual construction. The front glass or window 8 is customarily mounted in guides at the sides and is adapted to be let down into a slot 9, when desired, a hinged strip or covering 11 being employed to hold the window in position and also close the top of the slot 9. The parts thus far described may be of any usual or preferred construction.

In cold and stormy weather the sleet and snow have a tendency to lodge against and freeze upon the front glass 8 so as to seriously interfere with the driver's view. My present invention is designed to provide a shield for this glass which will protect it from sleet, rain and snow and maintain at least a portion of the glass clear through which the roadway may be observed. With this end in view I have provided a shield 12 consisting preferably of a frame with glass set therein and have, by means of a false top 13, formed a pocket or guide-way 14 in the front of the body and just beneath the

roof 6 adapted to receive and contain the storm shield 12. The front of this pocket or guide-way when the shield is disposed therein is normally closed by a door 15 preferably hinged at 16 so that the shield is entirely concealed in the top of the machine when not in use.

In the event of a storm, or whenever it may be desirable to utilize the shield the window 8 may be lowered a short distance so that the occupant of the machine may reach out, open the door 15 which may be secured by buttons 20 or otherwise to the cornice or top, as shown, in dotted lines in Fig. 2, and then draw the storm shield from the position shown in full lines to the operative position indicated in dotted lines. If preferred the door 15 may be mounted on a spring hinge which normally holds it in closed position and the door, instead of being buttoned in open position to the top, may rest against the upper face of the shield where it will be held against rattling by the force of the spring hinge. It will be observed that the rear edge of the shield frame is provided with a shoulder 17 adapted to abut against and engage with the body molding 18 which is suitably shaped to accommodate the shoulder 17 which serves to retain the shield in position and prevent its sliding out of the pocket. For the purpose of preventing sleet, etc., from driving in at the ends of the shield, I prefer to attach to the shield ends gusset flaps 19 which, when the shield is in operative position may be buttoned to the front of the body thereby holding the shield down in position and preventing its jiggling about. When the shield is not in use the flaps 19 may be thrown over onto the upper face of the shield and carried into the pocket therewith. The gusset flaps may be made of any suitable material, celluloid bound with leather being well suited for the purpose for the reason that it will permit the passage of light and will not obscure the vision.

It will be manifest from the foregoing that I have provided a disappearing storm shield which, when not in use, is concealed in the top of the vehicle, and, which can be readily withdrawn and disposed in operative position when required without getting out of the machine. The shield protects the glass front from sleet, snow, etc., the gusset flaps protect the glass at the ends of the shield, and the whole construction is

designed to be employed with the window 8 either up or down.

While I have shown and described a preferred embodiment of the invention, it 5 will be obvious that the structural details disclosed are capable of considerable modification and variation without departing from the principle of the invention.

I claim:

- 10 1. An automobile body having a driver's seat, a transparent wind shield in front of the seat, and means for shielding an upper portion of said wind shield against rain, sleet, hail, snow, etc., comprising a rigid storm shield slidably supported within the top portion of the body above and in rear of the wind shield and capable of being projected forwardly over the top of the wind shield and tilted downwardly and forwardly 15 across the upper portion of said wind shield into shielding position, and means to support the storm shield in its operative position.
- 20 2. An automobile having a driver's seat, a transparent wind shield in front of the seat, and means for shielding the upper portion of said wind shield against rain, sleet, hail, snow, etc., comprising a guideway within the top portion of the body and opening forwardly across the top of the wind shield, a storm shield slidably in the guideway and capable of being projected outwardly through the open front thereof beyond the transparent wind shield and tilted 25 downwardly across the upper portion of the wind shield into an operative position, and means to support the shield in its operative position.
- 30 3. An automobile body having a driver's seat, a transparent wind shield in front of the seat, and means for shielding the upper portion of said wind shield against rain, sleet, hail, snow, etc., comprising a rigid storm shield for the upper portion of the

wind shield, said storm shield being normally housed in an operative position within the top portion of the body, means to permit of the storm shield being moved outwardly through the front of the body and across the top of the wind shield into an operative position with respect thereto, and stop means to limit the outward movement of the shield when said shield has been brought into its operative position, said stop means permitting of the storm shield being pushed back into its inoperative position within the top of the automobile body.

4. An automobile body having a driver's seat, a transparent wind shield in front of the driver's seat and capable of being lowered into an inoperative position, means for shielding the upper portion of said wind shield against rain, sleet, hail, snow, etc., and comprising a rigid storm shield, the top portion of the automobile body being provided with a pocket located above the top of the transparent front for the reception of the storm shield when not in use, said pocket opening forwardly over the top of the transparent front, and a removable closure for the open front of the pocket and accessible from the interior of the body across the top of the transparent front when it is let down, said storm shield being slidably mounted in the pocket and capable of being slid forwardly through the open front of the pocket and then tilted downwardly into an operative position across the top portion of the transparent front, there being a stop projection on the rear end portion of the shield for engagement with the upper side of the pocket at the open end thereof to limit the forward movement of the shield when it has reached its operative position.

RICHARD A. GRIEFEN.
